UNITED STATES PATENT OFFICE.

SIMON COTHERMON, OF CONSTANTINE, MICHIGAN.

SHIFTING-RAIL FOR BUGGY-SEATS.

SPECIFICATION forming part of Letters Patent No. 326,019, dated September 8, 1885.

Application filed June 20, 1885. (No model.)

To all whom it may concern:

Be it known that I, SIMON COTHERMON, of Constantine, in the county of St. Joseph and State of Michigan, have invented a new and useful Improvement in Shifting-Rails for Buggy-Seats; and I do hereby declare that the following is a full and exact description of the same, reference being had to the accompanying drawings, and to the letters of reference 10 marked thereon.

The objects of this improvement are greater simplicity and economy in the construction of parts employed for and greater convenience in attaching shifting rails to and detaching the same from buggy-seats. These results are attained by the mechanism illustrated in the drawings herewith filed as part hereof, in which the same letters of reference denote the same parts in the different views.

Figure 1 is a rear elevation of a buggy-seat provided with my improved means for attaching and detaching the shifting-rail. Fig. 2 is a front view of the same. Fig. 3 is a side elevation. Fig. 4 is a sectional view taken on 25 the line $x x$ of Fig. 3.

A is the buggy-seat, provided with a series of seat-irons, a , fixed thereto in the usual manner. The seat-irons are provided at their outer ends with integral circular heads a' , having 30 perforations for the reception of screw-threaded shanks b^2 of lazy-back irons B B, which are secured in the position shown by means of the nuts b' and screws, as shown at b^3 , Fig. 2.

D D are lazy-back irons having screw-threaded shanks d and integral extensions or prongs D' , provided with screw-threaded shanks d' . The lazy-back irons D are secured to the lazy-back C in the ordinary manner, as shown at d^4 , and to the seat-irons $a a a a$ by 40 nuts $d^2 d^3$, as fully shown in Fig. 3.

E is the shifting-rail, having one straight and one convexed side. $E' E^2$ are integral extensions of the rail E, forming the props for the top or cover. (Not shown.)

45 The lazy-back irons B B and D D' D D' are filed or otherwise cut away to form dovetail projections, which fit over the convexed side

of the shifting-rail E, as shown at $b b$, Fig. 1, $b c c'$, Fig. 3, and more fully shown at c , Fig. 4. The circular heads a' of the seat-irons a 50 are filed or otherwise cut away to form dovetail projections a^2 , which also fit over the convexed side of the rail E, as fully shown in Figs. 2, 3, 4.

a^5 represents integral extensions of the front 55 seat-irons, which are additionally secured to the seat A by screws, as shown at a^6 , and form handles for use in entering the vehicle to which the mechanism is attached.

By means of the nuts $d^2 d^3$ on the screw-threaded shanks of the lazy-back irons D D' and the nuts b' on the screw-threaded shanks of the irons B the shifting-rail E is firmly clutched between the dovetail projections $b c$ 65 c' of the lazy-back irons and the dovetail projections a^2 of the seat-irons a . By loosening the nuts d^2 , d^3 , and b' sufficiently to clear the dovetail projections b of the irons B from the rail E the latter may be removed from the seat 70 without detaching and replacing the lazy-back. 70

I am aware that by reason of the patent to Fuller, September 24, 1878, the within-described mechanism is not broadly new; but

What I claim, and desire to secure by Letters Patent, is—

The shifting-rail E, having one convexed 75 and one perpendicular side meeting in sharp edges, in combination with the seat-irons a , having circular heads a' , provided with dovetailed recesses for fitting over the lower edge 80 of the shifting-rail, the lazy-back irons B, provided with dovetailed recesses for fitting over the upper edge of the shifting-rail, and the lazy back irons D D', provided with dovetailed 85 recesses for fitting over the upper edge of the shifting-rail, and arranged to secure the position of the same, as set forth.

In testimony whereof I affix my signature in presence of two witnesses.

SIMON COTHERMON.
